UNITED STATES PATENT OFFICE.

ROBERT V. JONES, OF CANTON, OHIO.

IMPROVED RAILROAD-RAIL.

Specification forming part of Letters Patent No. 56,760, dated July 31, 1866.

To all whom it may concern:

Be it known that I, ROBERT V. JONES, of Canton, in the county of Stark and State of Ohio, have invented certain new and useful Improvements in Railroad-Rails; and I do hereby declare that the following is a full, clear, and exact description of the same, reference being had to the accompanying drawings, and to the letters of reference marked thereon.

By reference to the drawings it will be seen that this rail is made in two parts, A representing the bottom or base of the rail, and B the top, the two parts, when secured together, resembling very much in appearance the ordinary T-rail.

The upper part of the rail is provided with a tongue on its under side which passes or sets into a groove in the lower part, A. The two flanges D D, which form the sides of the grooves in the lower part, A, are beveled upon their upper edges so as to fit into V-shaped grooves on the under side of the part B.

G represents a bolt, which passes through openings in the two parts where they are joined in order to confine them together.

By reference to the drawings it will be seen that the tongue E has a peculiarity of construction which I will describe. From x x (points a little above the curved end of the tongue) to z z the tongue is made concave on both sides, and from z z to a a the thickness of the tongue is diminished gradually a little. For instance, if the thickness of the tongue is one inch and a sixteenth from z to z, the thickness should be decreased to one inch from a to a, making a decrease of one-sixteenth.

The object in making the tongue concave on each side is, that when the bolt G is put through the two parts the two flanges D D may be sprung in a little to the tongue by means of the nut upon the end of the bolt, for the pur-

pose of leaving spring-pressure upon the nut to prevent it from jarring loose by the continual vibrations of trains passing over it.

The object in decreasing the thickness of the tongue from z to a is, that when the train passes over or is upon the rail B its weight will cause the beveled edges of the grooves from a to c to press upon the corresponding beveled edges of the flanges and force the said flanges tightly against the tongue. Forcing the flanges at or near their upper ends against the tongue, springing it slightly over the bulge at z, effects the double object of binding the flanges to the tongue, and thus making a tight joint, and also of causing a tendency of the flanges to spring out below the bulge at z, to more effectually prevent the nut which binds the two parts together from moving.

When the train is upon this rail a tight joint is made between the two parts by the weight of the train, as has been stated. This prevents rattling of the rails. As soon as the train leaves the rail the two parts of said rail, by their construction described, relieve themselves, and are sufficiently free to prevent damage from expansion or contraction of the parts.

What I claim as new, and desire to secure by Letters Patent, is—

The top rail provided with a tongue, E, upon each side of which are V-shaped grooves, said tongue being made concave on its sides below its center, and decreasing in size or width from z z to a a, when used with the flanges D D, with beveled edges and straight sides, substantially as and for the purpose herein specified.

ROBERT V. JONES.
